DESIGN FOR A BOTTLE

Edwin M. Fleischmann, Baltimore, Md., assignor to The Calvert Distilling Company, Relay, Md., a corporation of Maryland

Application May 2, 1935, Serial No. 56,661

Term of patent 14 years

To all whom it may concern:

Be it known that I, Edwin M. Fleischmann, a citizen of the United States of America, residing at Baltimore, State of Maryland, have invented a new, original, and ornamental Design for a Bottle, of which the following is a specification, reference being had to the accompanying drawing, forming part thereof.

In the drawing:

The decorative surface of the bottle is regarded as the dominating feature of the design.

I claim:

The ornamental design for a bottle as shown and described.

Signed by me at Baltimore city, Maryland, this 16th day of April, 1935.

EDWIN M. FLEISCHMANN.
